EUGENE B. LAMB AND FREDERICK C. ROBINSON, OF PORTLAND, MAINE.

WINDOW-CLEANING DEVICE.

1,035,796.

Specification of Letters Patent.

Patented Aug. 13, 1912.

Application filed February 18, 1911. Serial No. 609,496.

To all whom it may concern:

Be it known that we, EUGENE B. LAMB and FREDERICK C. ROBINSON, citizens of the United States, and residents of Portland, in the county of Cumberland and State of Maine, have invented an Improvement in Window-Cleaning Devices, of which the following description, in connection with the accompanying drawings, is a specification, like letters on the drawings representing like parts.

Our invention relates to window cleaning devices, and more specifically aims to provide an improved window cleaner for use particularly on electric cars, motor cars, pilot-houses of steamers and similar places where it is desirable to frequently remove from the glass rain, snow, sleet, dust, etc.

In the drawing showing an illustrative embodiment of our invention as applied to a conventional form of window, as, for instance, a window of a vestibuled electric car, Figure 1 is an elevation of the out-side of such a window with our improved attachment secured thereto, parts thereof being broken away; Fig. 2, an elevation of the in-side of said window, parts of the frame being broken away; Fig. 3 a vertical section on the line 3—3 Fig. 1; Fig. 4 an enlarged section detail on the line 4—4 Fig. 1, looking down; Fig. 5 illustrates various modifications of the supporting guide or track; and Fig. 6 a modification of the carrier.

Referring first to Fig. 1, the window frame 1 is provided at two opposite edges thereof, and herein at its top and bottom, with guide supports or tracks 2, 3, herein shown as hollow, tube-like members, secured, Figs. 1 and 4, at their ends to posts 4, secured in turn by means of plates 5, to the frame 1. The posts 4 and plates 5 may, for convenience, be constructed integral with each other. The members 2, 3, may be tubular, or they may be flat plates rolled into substantially tubular form, or they may be of any desired form in cross-section, see Fig. 5, and may, Fig. 4, be simply received in apertures in the posts 4, or they may be threaded therein or otherwise secured thereto. The posts 4 are drilled, or otherwise provided with passages therethrough, and said passages are adapted to register with apertures 6 through the window frame. Carriers or carriages 7, 8, of suitable form, and which herein are shown as substantially cylindrical, are mounted within said guides

2, 3, and are thereby securely housed and protected from sleet, snow and any other danger that might threaten to interfere with the free operation thereof. These members may be of any suitable material but are preferably of metal and have a sliding fit in said tracks and they serve to carry and guide the cleaner across the glass. These carriers may, if desired, see Fig. 6, be provided with roller or ball bearings 7^a, but it is not necessary.

The cleaner, Figs. 1 and 3, may comprise a back 9, preferably in the form of a long, narrow member, provided at one face with a narrow locking strip 10, secured thereto as by screws 11, to lock between said back and said locking strip a cleaner 12, of felt, rubber or any suitable material. Said cleaner 12 may be provided with laterally extending solts 13 so that it may be adjusted to or from the glass as required. To secure said cleaner to the carriers 7, 8, we provide hangers 14, 15, which may be secured to the back 9 by screws 16, slots 17 in said hangers permitting longitudinal adjustment thereof, if desired, relative to said back. The upper hanger 14 extends through a longitudinal slot or aperture 18 in the under side of the guide or track 2 and is received by a slot 85 in the lower side of the carrier 7, where it is shown, Fig. 3, secured by a screw 19. This screw may be readily inserted and removed by sliding the carrier along the guide toward the right until the head of the screw is opposite the opening 20 in the rear side of the guide 2, which permits a screw driver to be inserted for that purpose. The lower hanger 15 is hook-shaped in form herein, also extends upwardly through a longitudinal slot or aperture 21 in the lower side of the guide 3 and enters a similar slot in the carrier 8 where it may be secured, if desired, but it is not necessary as it cannot become detached from the carrier 8 without first detaching the upper hanger from its carrier 7. In order to actuate said carriers to operate the cleaner we may secure to the ends of said carriers, by any suitable means, as herein by eyes 22, cords, chains or similar members 23, which may be countersunk in the ends of the carrier if desired to make the arrangement compact, carried over rolls 24, Fig. 4, at the ends of the guides 2, 3, and herein mounted in said guides and thence through the post 4 and frame 1, thence over rolls or pulleys 25 se-

cured in the recesses 6 of the window frames, to a drum 26, of similar member, provided with a suitable handle 27, and secured, for instance, conveniently to the car body.

5 When it is desired to clean the glass of rain, snow, sleet or the like, one grasps the handle 27 and herein gives the drum 26 a half turn and thereby moves the cleaner across the glass effectually cleaning the 10 same. The next time it is desired to clean the glass the cleaner may be moved back to its former position in the same manner or, of course, the cleaner may be moved across the glass as many times as desired. The 15 drum may be inclosed in a suitable case 28, if desired, provided with an opening 29 to receive the handle 27.

Our improved cleaner combines the advantages of simplicity of construction with 20 certainty of operation. The cleaner being securely held at both ends by the carriers, in position against the glass, is always pressed against the glass with sufficient pressure to cause it to remove the moisture more effectively than would be the case if it were held against the glass by spring pressure only. The slots in the guides 2, 3, being on the 25 lower side of said guides cannot become filled with snow and ice and the cleaner 30 thereby rendered useless.

Doubtless modifications of the foregoing construction may be devised, for accomplishing the same purpose, without departing from the spirit and scope of our invention.

Claims:

1. A window cleaning device comprising a laterally operative cleaning member, a back member secured thereto, carriers, horizontal concealed tracks for said carriers, hangers secured to said back and said carriers and adapted to travel in concealed apertures in said tracks, and an operating member operatively secured to said carriers.
- 45 2. A window cleaning device comprising a cleaning member, carriers therefor adjust-

ably secured thereto for adjustment of said cleaning member in a plurality of directions, tracks for said carriers adapted to cause said cleaning member to travel in either direction at a substantially fixed distance from the window, means to positively actuate said cleaning member in either direction, and locking means for locking both of said carriers to said cleaning member at the same time.

3. A window cleaning device comprising a cleaning member, hollow tracks provided with apertures in their lower faces and hollow supporting posts therefor, carriers in 60 said tracks having a sliding fit therein and connected to said cleaning member, operating members extending through said tracks and posts for operating said cleaning member.

4. A window cleaning device comprising a cleaning member, hollow tracks provided with downwardly opening apertures therein and hollow supporting posts therefor, ball bearing carriers in said tracks connected to 70 said cleaning member, operating members extended through said tracks and posts and an operating drum at the opposite side of said cleaner from said tracks.

5. A window cleaning device comprising 75 a cleaning member, hollow tracks provided with downwardly opening apertures therein and hollow supporting posts for said tracks, carriers in said tracks having a close fit therein, hangers secured to said cleaning 80 member and the lower faces of said carriers, locking means for locking one of said hangers to a carrier and means in one of said tracks for operating said locking means.

In testimony whereof, we have signed our 85 names to this specification, in the presence of two subscribing witnesses.

EUGENE B. LAMB.

FREDERICK C. ROBINSON.
